UNITED STATES PATENT OFFICE.

WILLIAM LANG, OF BROOKLYN, NEW YORK.

COIN-CONTROLLED VENDING APPARATUS.

SPECIFICATION forming part of Letters Patent No. 431,366, dated July 1, 1890.

Application filed March 13, 1890. Serial No. 343,775. (No model.)

To all whom it may concern:

Be it known that I, WILLIAM LANG, of Brooklyn, in the county of Kings and State of New York, a citizen of the United States, have invented certain new and useful Improvements in Coin-Controlled Vending Apparatus, of which the following is a specification.

This invention relates to an improved coin-controlled vending apparatus of that class in which a coin of a normal size and shape has to be inserted for releasing the delivery-slide and permitting the delivery of merchandise from the merchandise-chute; and the invention consists of a vending apparatus which comprises, first, a merchandise-delivery slide having an opening that registers or corresponds with the lower end or mouth of a merchandise-chute and a second opening for inserting a coin of the required size; secondly, a pivoted and spring-actuated dog that engages the delivery-slide and prevents it from being released unless a coin of the proper thickness is inserted; thirdly, a pivoted and spring-actuated wedge-piece that is arranged sidewise of the dog and adapted to enter the coin-opening of the slide-piece whenever a smaller coin is inserted into the coin-opening; fourthly, a receptacle communicating with the coin-opening of the delivery-slide when the same is pushed back, so as to drop the coin, and, lastly, a merchandise-delivery chute by which the merchandise that is taken up by the delivery-slide is conveyed to and delivered at the lower front part of the apparatus, all as will be fully described hereinafter, and finally pointed out in the claims.

In the accompanying drawings, Figure 1 represents a vertical longitudinal section of my improved coin-controlled vending apparatus. Figs. 2 and 3 are vertical longitudinal sections of the locking device drawn on a larger scale, showing it, respectively, in position for locking the delivery-slide and for clearing it when a coin of the proper size is inserted. Fig. 4 is a vertical transverse section on the line 5 5, Fig. 5. Figs. 5 and 6 are plan views of the locking device, showing it in position before a coin is inserted, and in locked position when a coin of a smaller than the normal size is inserted. Fig. 7 is a ver-

tical longitudinal section of a modified construction of my improved vending apparatus, showing a modified construction of the merchandise-chute; and Figs. 8 and 9 are respectively a coin-opening and coin of a specific shape, adapted to be used in connection with the apparatus shown in Fig. 7.

Similar letters of reference indicate corresponding parts.

Referring to the drawings, A represents the exterior casing of my improved coin-controlled vending apparatus, which casing is provided with a vertical merchandise-chute B, in which the merchandise to be delivered is placed. This merchandise-chute may be either a single chute, as shown in Fig. 1, in which case it is used for delivering tablets of chocolate or other confectionery, or it may be arranged with a number of merchandise-chutes, arranged one back of the other, and which are open at the lower ends, as shown in Fig. 7, in which latter case the apparatus is adapted more especially for the vending of silk and other spools in factories in which a large quantity of spools are used and sold to the girls at cost-price. Below the lower end of the merchandise-chute B is arranged a delivery-slide C, which is guided in horizontal ways *a a* of the casing A and provided with an opening *b*, that registers or corresponds with the lower end of the merchandise-chute B, so that a piece of merchandise is delivered into said opening when the same is vertically below the mouth of the merchandise-chute B. In the lower front part of the casing A is arranged a coin-receptacle D, and back of the same an inclined chute E, which extends from the rear part of the casing A to the lower front part of the same, so as to form a delivery-chute for the merchandise dropped when the delivery-slide C is pushed inwardly.

The delivery-slide C is provided with a longitudinal groove or depression *d* and with a coin recess or opening *d'* about midway of said longitudinal groove *d*. That portion of the groove *d* back of the coin-opening *d'* is of lesser depth than that part of the groove *d* in front of the coin-opening *d'*, for the purpose of permitting the use of coins of the same denomination, but of different thickness, as is, for instance, the case in different issues of the one-cent and five-cent pieces.

The front end of the delivery-slide C is provided with a handle C', which serves for pushing the delivery-slide in backward direction and returning it into its normal position. (Shown in Figs. 1 and 5.)

To the ears of the upper front wall of the casing A, above the longitudinal groove d of the delivery-slide C, is pivoted a spring-actuated dog C², the lower inclined end of which moves 5 in said longitudinal groove d and serves to arrest the backward motion of the delivery-slide C by dropping into the coin-opening and engaging thereby the delivery-slide C, as shown in Fig. 2, whenever the same is to be 10 pushed in without placing a coin into the coin-opening d'. Sidewise of the delivery-slide C is arranged in a recess e at the top of the front part of the casing A a pivoted dog C³, that is provided with a beveled edge, said dog being 15 acted upon by a spring e', so as to be forced inwardly into the coin-opening d' whenever either a coin of smaller than the required size or a blank of pasteboard or other soft material is placed into the coin recess or opening 20 d'. For this purpose the coin-opening d' is placed near one edge of the slide-piece C, so as to communicate with a portion of its circumference with the recess e, so as to permit the entering of said dog when a smaller coin 25 or token or a pasteboard blank is placed into the coin-opening of the slide with a view to produce the operation of the apparatus thereby. The vertically-operated dog C², as well 30 as the laterally-movable dog C³, are inclosed 35 by a suitable box C⁴, so as to be entirely out of sight and not accessible, said box serving as a protection for the dogs, so as to prevent tampering with the same.

In front of the guard-box C⁴ is arranged, at 40 right angles to the delivery-slide C, a lateral groove f, which is in line with the side recess of the coin-opening d' when the delivery-slide is in normal position. The lateral groove f permits the introduction of a knife-blade, pin, 45 or other device, so that a coin of smaller size or greater thickness which has been inserted by mistake into the coin-opening can be removed again by the owner when the apparatus is not opened and no article of merchandise delivered therefrom.

For operating the vending apparatus a coin of the proper size, which fits exactly into the coin-opening d' and is of equal thickness with that part of the delivery-slide immediately in 55 front or back of the same, is dropped in the coin-opening d', and the delivery-slide then moved in backward direction—that is to say, pushed into the casing A—so as to move the merchandise, which is at the time in the inner 60 recess b of the delivery-slide, in backward direction and drop it into the inclined delivery-chute, along which it slides to the delivery-opening at the lower front part of the casing A, where it is removed by the owner. When 65 the coin in the delivery-slide C arrives over a corresponding opening d² in the top part of the casing A, it is dropped through said open-

ing and stored in said receptacle D. When a coin of the proper thickness is used, the vertical dog C² passes from the rear part of the longitudinal groove d over the coin into the front part of the groove, where the delivery-slide is of less thickness, without stopping the delivery-slide, which is thereby enabled to pass back of the dog C² and drop the merchandise into the delivery-chute. When a coin or token of greater thickness is inserted into the coin-opening, the same abuts either against a stop d³ of the casing C⁴ or against the dog C², so that the backward movement 70 of the delivery-slide and thereby the operation of the apparatus is prevented. When a coin of smaller diameter is dropped into the coin-opening of the delivery-slide, the laterally-swinging dog C³ is called into operation, the same being forced sidewise into the coin-opening, so as to prevent the further backward movement of the delivery-slide C, as shown in Fig. 6, where a smaller coin is shown. When a pasteboard blank 75 is dropped into the coin-recess d', the beveled or knife edge of the dog C³ enters or cuts into the pasteboard blank and locks the delivery-slide and prevents it from being pushed in. The front stop d³ of the casing C⁴ acts also as a protection for the vertically-pivoted dog C² as the stop enters into the rear part of the groove d, and prevents thereby 80 the insertion of a blade or other thin instrument, by which the lifting of the dog C² and the backward pushing of the delivery-slide C 85 may be produced.

When the vending apparatus is used for selling spool cotton or silk in clothing or other factories where the girls have to buy their own spools, the laterally-swinging dog C³ is dispensed with. In this case the vertically-pivoted dog is used in connection with the delivery-slide C, and with a token of any suitable arbitrary configuration, as shown in 90 Fig. 9. This token is placed into a coin-recess of corresponding shape, so as to permit the spring-actuated dog C² to pass over said token and enable the delivery-slide to deliver a spool from one of the series of merchandise-chutes B arranged in the casing A, as shown 95 in Fig. 7. The tokens are dropped into a receptacle D in the same manner as the coins in the apparatus shown in Fig. 1. The delivery-slide C is provided with a drop-chute 100 b' of the size of the bottom opening of the merchandise-chute. When all the spools in the spool-chute near adjacent the rear side of the casing are delivered, the next chute delivers its spools to the drop-chute b' of the 105 delivery-slide, and so on, one chute after the other until all the spools from all the chutes are delivered. In this case a guideway B' is arranged below the chutes B, the opening for dropping the spool being arranged back of 110 the rear end of said guideway, where it connects with the delivery-chute.

If an apparatus of the kind described is put up on each floor of a factory, the girls can

buy the token in the office and obtain the spools whenever they require the same without the attendance of a clerk or other employé.

5 Having thus described my invention, I claim as new and desire to secure by Letters Patent—

1. The combination of a merchandise-chute, a delivery-slide guided in ways below the same and provided with an opening for the merchandise below the chute and with a second or coin opening, and a spring-actuated dog sliding on the top part of the delivery-slide and permitting the backward motion of the same when a coin of the proper thickness is placed into the coin-opening, substantially as set forth.

2. The combination of a merchandise-chute, a delivery-slide having an opening corresponding with the bottom opening of the merchandise-chute, a coin-opening in the front part of the slide, and a longitudinal groove extending at both sides of the coin-opening, and a pivoted and spring-actuated dog that engages the longitudinal groove of the delivery-slide, substantially as set forth.

3. The combination, with a series of merchandise-chutes, a delivery-slide having an opening corresponding in size with the bottom opening of said chute, and a coin-recess in the front part of the side, and a spring-actuated locking-dog pressing on said delivery-slide, substantially as set forth.

4. The combination, with a merchandise-chute, a delivery-slide guided in ways below the same, said delivery-slide being provided with an opening corresponding in size with the bottom opening of said chute, and a sec-

ond or coin opening having a side recess, a vertically-swinging and spring-actuated dog 40 pressing on the top of the delivery-slide, and a laterally-swinging and spring-actuated dog having a wedge-shaped edge that is adapted to enter the side recess of the coin-opening when a coin of less than the required size is 45 placed into the coin-opening, substantially as set forth.

5. The combination, with a merchandise-chute, of a delivery-slide having an opening corresponding in size with the bottom opening of said chute, and a coin-opening with a recess at one side of the same, and a lateral channel communicating with the side recess of the coin-opening, so as to permit the removing of coins of smaller size or greater 55 thickness than the required size which are inserted into the coin-opening, substantially as set forth.

6. The combination of a merchandise-chute, a delivery-slide below the same, said delivery-slide having an opening corresponding in size with the bottom opening of said chute, a second or coin opening and a longitudinal groove extending at both sides of the coin-opening, a pivoted and spring-actuated dog engaging 65 said groove, and a casing inclosing said dog and provided with a guard-stop engaging the longitudinal groove of the delivery-slide, substantially as set forth.

In testimony that I claim the foregoing as 70 my invention I have signed my name in presence of two subscribing witnesses.

WILLIAM LANG.
